UNITED STATES PATENT OFFICE.

EDWARD M. KNIGHT, OF BROOKLYN, NEW YORK.

FILTERING MEDIUM.

Application filed June 9, 1922. Serial No. 567,296.

To all whom it may concern:

Be it known that I, EDWARD MARTIN KNIGHT, a citizen of the United States, and residing at 467 Vanderbilt Avenue, Brooklyn, in the county of Kings and State of New York, have invented certain new and useful Improvements in a Filtering Medium, of which the following is a clear and exact specification.

10 This invention relates to filtering media for use in filters intended for purifying water, and my present improvement, which comprises a development of my earlier Patent No. 1,318,388, includes a new product 15 constituting a filtering element and also the steps employed in the process whereby this product is created.

15 In my said earlier patent I have disclosed a filtering medium composed of two superimposed sheets of fibrous material with an intermediate layer of carbon, the sheets of fibrous material being clamped together at their edges to thereby contain the carbon.

20 Further experiments conducted by me have resulted in the formation of the superimposed sheets into an interlocking cellular structure which divides the area of the medium into a number of carbon containing 25 pockets and thereby prevents the dispersion 30 of the carbon contents.

The new product therefore consists of two sheets of fibrous material with an intervening layer of carbon, the whole structure being moulded into a number of separate cells 35 to localize the carbon contents; and the steps leading to the production of this product consist in applying a thin layer of carbon, either in powdered or paste like form, upon 40 a sheet of fibrous material; placing another sheet of fibrous material upon the exposed carbon; placing the ply elements upon a yielding surface, and then applying a male die with pressure to impress into the ply material a series of right angular 45 depressions, thereby interlocking the fibres of the sheets and providing cells which confine the carbon.

50 The carbon, as formed into a paste or mass for convenience in applying it to the surface of one of the sheets, may include the admixture of a suitable adhesive as a binder, which will cause the superimposed sheets to adhere, and thereby give permanency to the cellular formation.

55 Other features and advantages of my invention will hereinafter appear.

In the drawings:

Figure 1 is a plan view of my improved filtering medium.

Fig. 2 is a plan view of one of the ab- 60 sorbent sheets before it has been moulded.

Fig. 3 is a plan view of another absorb- 65 ent sheet upon which a film of carbon has been placed.

Fig. 4 is a partial view of a mould com- 70 prising a flexible base which serves as a matrix and a male die member to co-act therewith, and

Fig. 5 is a section on an enlarged scale on the line 5—5 of Figure 1. 75

In carrying out my invention for the production of the improved filtering medium I employ two sheets of fibrous material, as indicated respectively at 1, 2. While these sheets are shown as of circular outlines, 75 they may be of other suitable shape.

Upon a surface of one of these sheets, as 1, I place a film of carbon, 2*, which may be in the form of powder or a paste. If in paste form then the liquid used may include a suitable adhesive. The other sheet, as 2, is then placed over the carbon film, and then the two ply material with its carbon filling is pressed in a mold which imparts a cellular structure thereto, indicated by the crossed depressions 3, 4 and the cells 5. 80

The mould employed by me for the purpose comprises a matrix 6, consisting of a flat surfaced pad of yielding material, such as rubber, and a male die member 7 having 90 on its surface the crossed ribs 8 that impress the two ply sheet material with their contour when pressing against the yielding matrix, and thereby impart the cellular form to the sheet material which is the 95 essential feature of the invention.

In this way a construction is obtained which will maintain the carbon film in unbroken form and prevent the crumbling or disintegration thereof in transportation or 100 by rough handling, or the use of the disk in a perpendicular position in a filter.

While the cells thus created for confining the carbon are here shown as rectangular in outline, they may obviously be given other 105 shapes without departing from the spirit of my invention.

Variations within the spirit and scope of my invention are equally comprehended by the foregoing disclosure. 110

I claim:—

As a new article of manufacture a filter

2
in which the layers of material are designed to be maintained in a vertical position, comprising three layers of material, consisting of two outer vertical layers of fibrous material and one interposed layer of carbon, the whole being pressed and indented along certain lines on one side, thereby forming cells on the opposite side, the walls of the indentations of the carbon layer following closely the indentations of the fibrous mate-

rial whereby a contacting locking means is provided for the carbon layer so that the thickness of the combined layers is uniform throughout, a maximum filtering surface provided, and the carbon layers secured from displacement and disintegration. 15

Signed at the borough of Manhattan, in the city, county and State of New York, this 5th day of June, 1922.

EDWARD M. KNIGHT.
